GRAPPLE

Filed May 7, 1929

UNITED STATES PATENT OFFICE

FRANKLIN L. FARNSWORTH, OF CLARKSTON, WASHINGTON

GRAPPLE

Application filed May 7, 1929. Serial No. 361,152.

My present invention relates to an improved grapple which, while adapted for various uses is particularly designed for use in hauling logs for storage or transportation

purposes. The grapple is of that type utilizing a plurality of hooked tongs, pivotally supported or hinged in a housing, and draft devices are used with the tongs for grappling the log and holding the log during the hauling or lifting operation.

The invention consists in certain novel combinations and arrangements of parts as will be hereinafter more fully set forth and claimed. In the accompanying drawings I have illustrated one complete example of the physical embodiment of my invention in which the parts are combined and arranged according to the best mode I have thus far devised for the practical application of the principles of my invention.

Figure 1 is a view showing the grapple attached to the end of a log. Figure 2 is a face view of the grapple as seen from the right in Figure 1. Figure 3 is an enlarged sectional view of the grapple at line 3-3 of Figure 1 with the hooks open. Figure 4 is a view similar to Figure 3 but with the hooks in closed position. Figure 5 is a detail perspective view of one of the tapered nuts used in the draw head. Figure 6 is a perspective view of the halved draw head. Figure 7 is a perspective view of one of the fulcrum blocks carried in the housing of the grapple.

In carrying out my invention I utilize a housing 1 of metal and preferably with a tapered exterior surface and an interior, cylindrical bore 2. A draw bar 3 projects through a hole 3' in the smaller closed end of the housing, and the bar is provided with an eye 4 to which the hoisting or hauling chain 5 is attached. The draw bar extends axially through the longitudinal center of the bore 2 and the end of the bar within the bore is fashioned with a reduced portion 6 having an end shoulder 7 and an end collar 8. The halved, round, draw head 9 is carried on the reduced end of the draw bar, and slidable in the bore of the housing, said draw head being made in two sec-

tions to facilitate mounting of the head on the end of the draw bar, and the head is fashioned with a central hole 10 for this purpose.

A plurality of grappling tongs, here shown as four, are indicated at 11 and provided with grappling hooks 11' for impingement into the surface of the log L. These tongs are radially or diametrically arranged about the axial center of the draw bar and draw head and they are carried at the large, open end of the housing in perforated ears 12 on hinge or pivot pins 13. These perforated ears are integral with fulcrum blocks 14 (four in number) each of which has a pair of flanges 15, and these blocks of T-shape are carried in complementary T-shaped slots 16 in the edge of the housing. The T-slots are of course diametrically arranged in the edge of the housing and the full wall of the cross portion of the T-slot is beveled, as indicated in Figures 3 and 4 for co-action with a complementary face of the fulcrum block, to insure a wedge action when the fulcrum block is forced into its slot. After the fulcrum block is in position it is locked in place by the use of a set screw or bolt 17. The T-slots and the T-blocks are of standard sizes and shapes, and the blocks may readily be renewed or replaced in case of breakage.

Each grappling tong is fashioned with an angular lever arm 18 at its pivoted end, and between the lever arm and the draw head a link connection 19 is provided, said link connections being pivoted to the lever arm at 20. At 21 the links are pivoted in eye-bolts 22, and these eyebolts are provided with clamp nuts 23 that are made resilient by slitting or splitting at 24. The clamp nuts are tapered or frusto conical in shape and they fit into complementary seats 25 that are enlarged from the bolt holes of the draw head. Lock nuts 26 are also provided for the eye-bolts, and it will be apparent that by turning home these lock nuts against the larger end of the clamp nuts, the split portions of the latter are compressed and clamped over the threads of the bolts for

the purpose of firmly anchoring the bolts in the draw head.

To facilitate the formation of the T-slots in the manufacture of the housing, these slots are extended through the wall of the housing, and the housing is provided with a counterbore or annular seat 27 in which a bushing 28 is fitted to close the openings at the inner ends of the T-slots. The fulcrum blocks and the bushing provide a bearing for the lever arm of the grappling hook when the strain of a pull is placed on the grapple, with the parts in position of Figure 4.

As indicated in Figure 1 the hooks 11^a impinge laterally against the outer face of the log and as the draw or pull on the chain 5 is exerted, the hooks are forced to grapple the log and hold it for the desired manipulation of the log. By grappling the log at the four diametrical points, the log may readily be hauled over a surface and swung to perpendicular position where it is suspended perpendicular to the ground, and in this position the hoisting mechanism may be used to swing or manipulate the log with greater freedom than if the log were suspended at an angle to the perpendicular.

The action of the draw bar and draw head may readily be understood from an inspection of Figures 3 and 4. In the former figure the grappling hooks are open and it will be apparent that an axial pull on the draw bar will cause the levers 18 to be swung inwardly by the links 19 as the latter are drawn into substantial alinement with the eyebolts 22. As the links are alined with the bolts the inner ends of the bolts contact with the base wall of the bore of the housing, and the angular edges of the levers 18 contact with the fulcrum blocks and the bushing. Thus the strains of the pull on the chain are distributed uniformly throughout the parts of the device and the grapple performs its functions with reliability and efficiency.

Having thus fully described my invention, what I claim as new and desire to secure by Letters Patent is:—

1. The combination with a housing and a plurality of grappling hooks pivotally supported thereon, of a draw bar and draw head, eyebolts in the head, links connecting said bolts with the hooks, tapered, resilient clamp nuts on the bolts and complementary seats for the nuts in the head, and lock nuts on the bolts.

2. The combination with a housing having a plurality of T-slots, T-blocks in said slots and fastening means for the blocks, of grappling hooks pivoted in the blocks and lever arms on the hooks, a draw bar and draw head in the housing, and linked connections between said arms and said head.

3. The combination with a housing having

a plurality of T-slots and a countersunk bushing closing the inner ends of said slots, of T-blocks in the slots and set screws for the blocks, said blocks having perforated ears and grappling hooks pivoted in the ears, lever arms on the hooks, a draw bar and a draw head in the housing, eyebolts carried by said head, and links connecting said eyebolts and the lever arms.

In testimony whereof I affix my signature.

FRANKLIN L. FARNSWORTH.
